(57) CLAIM

I claim the ornamental design for a modular sofa with USB charger, as shown and described.

DESCRIPTION

FIG. 1 is a Perspective view of a modular sofa with USB charger showing my new design;

FIG. 2 is a Front view thereof;

FIG. 3 is a Back view thereof;

FIG. 4 is a Right-side view thereof;

FIG. 5 is a Left-side view thereof;

FIG. 6 is a Top view thereof;

FIG. 7 is a Bottom view thereof; and,

FIG. 8 is Perspective view of a modular sofa with USB charger showing in zoom position.

The broken lines in the drawings depict portions of the modular sofa with USB charger that form no part of the claimed design.
